UNITED STATES PATENT OFFICE.

GEORGE T. SIMMONS, OF JANEVILLE, WISCONSIN.

SPARK-PLUG.

1,255,805.

Specification of Letters Patent.

Patented Feb. 5, 1918.

Application filed October 7, 1916. Serial No. 124,408.

To all whom it may concern:

Be it known that I, GEORGE T. SIMMONS, a citizen of the United States, and a resident of Janesville, in the county of Rock and State of Wisconsin, have invented certain new and useful Improvements in Spark-Plugs; and I do hereby declare the following to be a full, clear, and exact description of the invention, such as will enable others skilled in the art to which it appertains to make and use the same.

This invention relates to improvements in spark plugs for internal combustion engines,—one object of the invention being to provide a simple spark plug, which shall be so constructed as to effectually prevent collection of oil at the spark terminals.

A further object is to so construct a spark plug that the sparking terminals shall be so constructed and disposed within an apron extension of the plug casing as to prevent creeping oil from reaching the parts of said terminals between which the sparks are formed or generated.

With these and other objects in view, the invention consists in certain novel features of construction and combinations of parts as hereinafter set forth and pointed out in the claims.

In the accompanying drawings, Figure 1 is a sectional view of a spark plug embodying my invention, and Fig. 2 is a view of a modification.

1 represents the casing of a spark plug having an internally threaded enlarged upper portion 2 for the accommodation of suitable retaining means for the inner porcelain or insulated member 3 of the structure. The lower portion of the casing 1 is threaded externally as at 4 to screw through a suitable opening in the cylinder head of an internal combustion engine.

Below the threaded portion 4, the shell is made with an annular apron extension 5, the wall of which is made quite thin and is adapted to project inwardly beyond the inner wall of the combustion chamber of the engine cylinder.

Above the upper end of the apron 5, the bore of the casing 1 is contracted for a short distance, as at 6, thus forming at the upper end of said apron, an internal shoulder 7.

One of the sparking terminals which, for convenience may be called the inner sparking terminal 8, may consist of a straight wire carried by the porcelain body 3 of the

structure and depends therefrom centrally through the contracted bore 6 and the thin apron extension 5.

The other sparking terminal which, for convenience may be referred to as the outer sparking terminal 9, consists of a piece of wire secured at its upper end in a suitable socket formed in the internal shoulder 7. The wire of this sparking terminal extends from the shoulder 7 downwardly in a diagonal direction through the chamber formed by the apron 5 and at its lower end, said wire is bent upwardly to form a loop 10, the free member 11 of which projects upwardly within the chamber of the apron so as to be disposed in a substantially vertical position, and the extremity of the vertical member 11 of said outer sparking terminal wire is bent laterally, as at 12, so that its extremity shall be presented at right angles to the inner sparking terminal 8 within the apron chamber.

From the above description, it will be seen that the wire of the sparking terminal 9 is not in contact with the wall of the apron but that it projects away from said wall toward the center of the apron chamber and that its free limb or member 11 is so disposed and of such length as to prevent the climbing of oil to its free extremity.

The oil which finds its way on the cylinder walls to the plug will, upon reaching the thin depending apron pass down the same and what is not consumed will collect at the lower edge of said apron and at each firing will be forced back into the cylinder. Should the wall of the engine cylinder be very oily, some oil might find its way inside the apron and tend to creep up the same, but with my improved construction, wherein the outer terminal wire depends from a shoulder at the upper end of the apron and projects away from the wall of the apron, with a vertical free limb terminating within and near the center of the apron chamber, the oil would have to travel upwardly on the apron wall a considerable distance to reach the outer terminal wire, and this is not liable to occur. Should any oil find its way to the outer terminal wire it would be burned off this wire on passing down it on account of its length and should any happen to reach the bottom of this loop it would not be able to travel upwardly along the free vertical limb 10 to the sparking point 11.

Instead of providing an apron such as

shown in Fig. 1 the threaded portion 4 may be extended to the lower end of said casing as shown in Fig. 2. In this form of the invention, the casing is provided interiorly 5 above its lower end with an annular shoulder 13, to which the outer terminal wire 14 is secured, the same as in the construction shown in Fig. 1. In Fig. 2, the looped end 15 is shown as being curved 10 throughout and while said loop is shown projecting below the end of the casing, still the free terminal 16 is within the casing.

Having fully described my invention what I claim as new and desire to secure by Letters Patent, is:—

1. A spark plug comprising a casing, an insulator member supported in the upper portion of said casing, said casing having an internal shoulder located above the lower 20 end thereof and below said insulator member and its support, an inner electrode extending below said internal shoulder and spaced therefrom, and an outer wire electrode fixed at its upper end to said internal shoulder and extending downwardly and in- 25

wardly therefrom, said outer wire electrode terminating near the lower end of the casing and in sparking relation to said inner electrode.

2. A spark plug comprising a casing provided at its lower end with an integral depending apron adapted to project into the combustion chamber of an engine, said casing having an internal shoulder at the upper end of said apron, an inner electrode 35 entering the chamber formed by said depending apron, and an outer wire electrode fixed to said internal shoulder and projecting downwardly therefrom in a diagonal direction in the apron chamber and having 40 a sparking terminal projecting upwardly and inwardly toward the inner electrode.

In testimony whereof, I have signed this specification in the presence of two subscribing witnesses.

GEORGE T. SIMMONS.
